UNITED STATES PATENT OFFICE.

LOUIS R. HORTON, OF PROVIDENCE, RHODE ISLAND, ASSIGNOR TO THE
J. B. & S. M. KNOWLES COMPANY, OF SAME PLACE.

DESIGN FOR A HANDLE FOR SPOONS, &c.

SPECIFICATION forming part of Design No. 23,719, dated October 28, 1894.

Application filed August 17, 1894. Serial No. 520,632. Term of patent 7 years.

To all whom it may concern:

Be it known that I, LOUIS R. HORTON, of Providence, in the county of Providence and State of Rhode Island, have invented and produced a new and original Design for Handles of Spoons and Similar Articles, of which the following is a specification, reference being had to the accompanying drawings, forming part thereof.

10 Figure 1 is a representation of a handle attached to the bowl of a spoon and illustrating the obverse of my new design, the tine portion of a fork being dotted in position. Fig. 2 represents a reverse view of the same.

15 The leading features of my new design consist in the symmetrical outline of the handle gradually expanding toward the upper portion, broken at this upper portion by indentations, then curving again outward and ending over the upper end of the handle in a succession of short curves, together with surface ornamentation on the obverse consisting of line borders following the outlines of the lower portion of the handle, a succession of 20 gradually enlarged beads within the borders, an ornament with small scrolls located below these beads and between the borders, a group of floriations above the beads with scrolls extending downward toward the beads also between the borders, the upper ends of which borders are scrolled inward above the floriations, a central plain panel, scrolls at the sides of the panel, and an upper finishing border over the panel forming the upper end 25 of the handle consisting of series of scrolls. On the reverse the surface ornamentation consists of the line borders scrolled inward at their upper and lower ends and following the outline of the handle at this portion, inwardly-turned foliations overlapping these lines, and a scrolled border extending from the upper ends of these line borders around the upper portion of the handle following the general outline of the same and leaving a central plain surface.

In the drawings 5 represents the lower portion of the handle and 6 the bowl of a spoon. It may, however, represent the main portion of any similar article one of which is indicated in broken lines. The outline of the handle extends upward from the article to

which it is attached in symmetrical curving lines gradually expanding the width of the handle to 7-7, then contracting and expanding in a succession of short curves to 8-8, 55 then curving gradually outward and inward to 9-9 which points are connected by a succession of curves forming the outline of the upper end.

The obverse of the handle is ornamented 60 on the neck or shank portion of the line bead-borders 10-10 parallel with the edge of this portion of the handle and scrolled inward at the tops. Between these borders 10-10 at the lower ends is the ornament 11 from which the scrolls 12 extend, some of these scrolls overlapping the borders. Above this ornament are the beads 13 gradually enlarging as the width of the handle increases, the upper bead being connected by the scrolls 14 with 65 the grouped floriations 15 between the upper scrolled ends of the borders. At the sides of the plain panel 16 are the outwardly-extending scrolls 17-17 above which are the side scrolled-borders 18-18 and the top scrolled-ornament 19. On the reverse the ornamentation consists of the line bead-borders 20-20 scrolled inward at their ends and having the overlapping foliations 21-21, the borders following the outline of the neck of the handle 70 and joining the side scrolls 22-22, these connecting with the reversed scrolls 23-23 which are joined over the top of the handle by the scrolls 24 and the ornament 25, the whole forming a border for the central plain portion. 75

What I claim is—

1. In the design for the handle of a spoon or similar article the obverse as herein shown and described.
2. In the design for the handle of a spoon or similar article the reverse as herein shown and described.
3. The design for handles of spoons and similar articles as herein shown and described.

In witness whereof I have hereunto set my hand.

LOUIS R. HORTON.
